JUG OR THE LIKE

John L. Szajna, Norridge, Ill., assignor to Continental Can Company, Inc., New York, N.Y., a corporation of New York

Filed Mar. 3, 1965, Ser. No. 84,055

Term of patent 14 years

(Cl. D58—17)

The essential features of the design reside in the portions shown in solid lines.

I claim:

The ornamental design for a jug or the like, as shown and described.
